UNITED STATES PATENT OFFICE

CLARENCE E. JOHNSON AND FRED C. KOESTNER, OF CHICAGO, ILLINOIS

REGISTERING MECHANISM

Application filed October 6, 1921. Serial No. 505,787.

This invention relates to a registering mechanism.

We particularly aim to provide such a mechanism as is applicable to taximeters and we generally aim to improve and render a mechanism of this kind more efficient, and still enable manufacture thereof at minimum expense.

Many novel objects are attained as will appear from a consideration of the description following taken with reference to accompanying drawings illustrating one preferred embodiment, and particularly it is aimed to provide means to actuate the apparatus by a motor as for registering a fare for waiting time and actuate it from a vehicle wheel for running time and in connection with electro-magnetic make and break devices; to provide means whereby an increased fare or tariff can be registered; to provide a novel resetting mechanism for the registering drums; to provide novel detent means for the registering drums; to provide novel means for accommodating the operating frame for such drums; to provide improved clutch mechanism for certain drums and a novel means to actuate the same; to provide novel shutter mechanism for the registering drums and a means for registering extra charges.

In said drawings:

Figure 1 is a front elevation of a taximeter embodying our improvements;

Figure 2 is a rear elevation thereof;

Figure 3 is a side elevation of the taximeter partly broken away to disclose details;

Figure 4 is a diagrammatic view of the electrical equipment of the taximeter;

Figure 5 is a side elevation of the taximeter with the casing removed;

Figure 6 is an elevation from the opposite side to Figure 5 of the taximeter and with the casing removed;

Figure 7 is a front elevation of the taximeter with the casing removed;

Figure 8 is a plan view of the taximeter with the casing removed;

Figure 9 is a fragmentary front elevation, partly in section, of the taximeter taken in the rear of the supporting plate;

Figure 10 is a view substantially similar to Figure 9 but taken in advance of the supporting plate and with the flag in lowered position;

Figure 11 is a detail longitudinal cross-sectional view;

Figure 12 is a detail longitudinal cross-sectional view taken opposite to Figure 13;

Figure 13 is a fragmentary cross-sectional view taken through the registering drums and mounting means therefor;

Figure 14 is a detail fragmentary cross-sectional view through the taximeter substantially on the plane of the slide associated with the armature of the double electro-magnet;

Figure 15 is a partial inverted plan view of the taximeter;

Figure 16 is a vertical sectional view taken substantially along the line 17—17 of Figure 7;

Figure 17 is a fragmentary sectional view looking toward the rear of the supporting plate employed;

Figure 18 is a cross sectional view taken substantially along the line 19—19 of Figure 6;

Figure 19 is a plan view of the make and break device associated with an automobile;

Figure 20 is a side elevation thereof;

Figure 21 is a cross sectional view through the casing of said make and break device;

Figure 22 is a plan view of the cam ring used on an automobile wheel;

Figure 23 is a cross sectional view on line 24—24 of Figure 22; and

Figure 24 is a detail perspective view of the shaft upon which the number of fare drums of the registering mechanism are mounted.

Throughout the various views of the drawings, like reference characters designate like or similar parts.

In reducing the invention to practice, a suitable casing or enclosing structure is provided consisting of a back or base 1 adapted to support the operating parts and a cover or closure 2 detachable therefrom. Except in Figures 1 and 2, cover 2 has been omitted to disclose details. This cover 2 may be of any suitable shape and design and is preferably provided with a lug at 3 to rest in a hook lug 4 provided on the base 1 adjacent one end of the casing. Adjacent the other end of the casing, a securing latch in the form of a lever 5 is pivoted at 6 to a bracket 7 extending from the base and is engageable with the lug 8 within the casing and adapted to be urged against said lug through the adjustment of a set screw 9 passing through a suitable opening in which it is threaded to said base 1. It will be realized that normally the screw 9 is retracted to occupy the dotted line position shown in Figure 3 so that the casing 2 may be readily attached or detached. When attached, the lug 3 is placed in engagement with the hook 4 and thereafter screw 9 is moved inwardly to the full line position of Figure 3, thus tightening the latch lever 5 against the lug 8 and mounting the cover 2 rigidly on the base.

The front of the casing is preferably closed by a glass panel 2^a and with the exception of transparent portions 10, 12 and 13 is rendered opaque by the application of a coating of black paint to the inner surface thereof or in any other suitable manner. The transparent portion 10 has the words "Time" and "Recording" delineated thereon, between which a sign 11 is movable and which may contain the word "Not" to indicate when the device is, and when it is not recording. Operating in the rear of the portions 12 and 13 are registering or fare drums 14 and 15, respectively. The drums 14 form a register to indicate fare which the passenger normally must pay and drums 15 form a register for extra or fare to be added to that of drums 14 and to be paid by the same passenger. A plate 16 also operates in rear of the portion 12 having a zero mark to coact with drums 14 always forming the right hand figure as charges always end with zero. The panels 2^a may rest against lugs 2^b and be overlapped by a flange 2^c, and a felt or other waterproof filler 2^d may be interposed between the panel 2^a and the flange 2^c, as clearly shown in Figure 3 of the drawings.

Also visible from the front of the device is a flag or plate 17 having a stem 18 mounted on a stub shaft 19 journaled in the base 1. This flag is in raised position when the apparatus is not in service and it is in lowered position when the apparatus is in service.

A switch arm 20 is also visible from the

front of the apparatus and is mounted on a stub shaft 21 journaled in said base 1 (see Figures 4 and 9).

In the base 1 adjacent the lower end thereof is an elongated opening 22^a preferably covered by transparent material. Behind the opening 22^a and visible from the rear of the apparatus, are groups of recording drums forming a conventional registering mechanism 24.

Within the casing a disk 28 (Figures 9 and 10) is keyed or otherwise fixed on the stub shaft 19. This disk may slide a limited extent on the key and stub shaft 19 and is normally urged into frictional contact with the base 1 by means of an expansive spring 30 interposed between the disk 28 and a flange or head 31 on the stub shaft 19 (Figure 8) so that it may be frictionally held or automatically remain in its different positions through actuation of shaft 19.

Secured against the base 1 is a block of insulation 32 (see Figure 9) in which stub shaft 21 is journaled and across which a blade 22 rigid with switch arm 20 is operable. On block 32 a contact 33 is secured while a resilient contact 34 normally disengaged from contact 33 is disposed over it and relatively close thereto. On the disk 28, an arm 35 is provided. In the path of movement of said arm 35 contact 34 is disposed so that it will be engaged by said arm 35 in order to move it into contact with the element 33. Also mounted on the base or block 32 are contacts 36, 37 and 38. It will be noted that when the flag is raised, the arm 35 disengages contact 34.

Adjacent to the upper end of the base and spaced forwardly therefrom is a supporting plate 39 (Figures 8 and 17), mounted as by means of studs 40 extending from base 1 and screws 41 extending through the supporting plate 39 and into the studs. A suitable electric motor 42 (Figures 5 to 8) is mounted in any approved way from this plate 39. This motor controls a make and break device for fare registering mechanism when the vehicle equipped with it is not running so as to provide a charge for waiting time, and hence switch 20 (Figure 4) is thrown to the right for operation of the registering mechanism when the vehicle is running and is thrown to the left when the vehicle is idle as will later become more apparent. The main shaft of motor 42 is shown at 43, as in Figure 7, having one end journaled in a bracket 44 suitably supported from the plate 39. On the shaft 43, a conventional governor mechanism has been illustrated at 45. Journaled in supporting plate 39 is a shaft 46, which is also journaled in a bracket 47 fastened at 48 to the plate 39. On shaft 46, a gear wheel 49 is keyed or fixed which is in the nature of a worm wheel which meshes with a worm 50 keyed

or fixed on the shaft 43. A spur gear wheel or pinion 51 (Figure 10) is keyed or fixed on shaft 46 and meshes with a gear wheel 52 journaled on a shaft 53 extending from plate 39. Extending from gear wheel 52 is a cam stud 54 engageable with a contact 55 of an electric switch completed by a contact 56 (Figures 4 and 5) which is secured to a block of insulation 57 supported on plate 39 as by means of binding screws 58.

A vertical shaft to operate the registering mechanism as will be hereinafter specifically described, is illustrated at 59 and journaled in brackets or plates 60 and 61 extending outwardly from the base 1. Rigid with shaft 59 is a relatively large ratchet wheel 62 (see Figure 14) which is adapted to be rotated by a step-by-step movement of an armature 63 associated with a double electro-magnet at 64 suitably secured to the base 1. Said magnet 64 is controlled selectively by two make and break circuits, one operated by the motor 42 and the other by the wheels of a taxicab as will later appear so that "waiting time" as well as "running time" may be charged. The armature 63 has a mounting arm 65 journaled on the shaft 59. A preferably resilient pawl or arm 66 extends from armature 63 and is in normal contacting relation with the teeth of the ratchet wheel 62 so as to turn said ratchet wheel through movement of the armature 63 caused by the electro-magnet 64. An arm 67 projects forwardly from the base 1 and a contractile spring 68 is secured thereto and to arm 65 to normally maintain the armature 63 away from the magnet 64 and against a stop which limits its movement and which may be a set screw 69 operatively mounted in an arm 70 of a bracket 71. In order to prevent retrograde movement of the shaft 59 as the armature 63 is returned to normal position after an actuation of the ratchet wheel 62, a ratchet wheel 72 similar to ratchet wheel 62 is keyed or otherwise fixed to the shaft 59 above the same and a resilient pawl 73 (Figure 14) is tensioned to normally remain in contact with the teeth of said ratchet wheel 72 to prevent movement thereof. Pawl 73 may be fastened to the bearing plate 60 or another suitable part.

On the shaft 59 a gear wheel 74 is loosely journaled. Gear wheel 74 has a plate 75 rigid thereon carrying a pawl 76 to coact with a stud or projection 77 (Figure 7) on shaft 59 so that rotation of the wheel 74 or plate 75 will turn the shaft 59 in one direction. To turn gear wheel 74 in order to set up a minimum fare, a segmental rack gear 78 is provided and extends rigidly from the disk 28 (Figure 10). Thus rack 78 is operated by the flag 17 and its shaft and the shaft 59 through the medium of parts to be later described coact with registering mech-

anism. These parts are operated only when the cab is idle.

Said vertical shaft 59 is designed to operate any preferred type of registering mechanism. The actuation of shaft 59 is effected as follows. The flag 17 is thrown to the right in Figures 1 and 7 to occupy a concealed or dotted line position when the vehicle equipped with the apparatus starts a trip. Its movement to such position is limited by means of a bearing 79 (Figure 2) fastened to the back of base 1 and associated with stub shaft 19. This bearing 79 also limits the movement of the flag 17 to the full line or projected position in said Figures 1 and 7 in which it indicates that the aforesaid vehicle is vacant. By movement of the flag to the concealed position, stub shaft 19 turns the disk 28 and accordingly arm 85 to the right which depresses contact 34 into engagement with contact 33. The switch arm 20 may also be thrown to the left for instance, so as to simultaneously engage the contacts 37 and 38, reference being had to Figures 9 and 4, particularly the latter. Thus an electric circuit from a source of energy such as an electric battery, is established through the motor 42 and the double electro-magnet 64 and switch contacts 55 and 56 when closed by the cam 54. Figure 4 illustrates the electric circuit as controlled by switch 22. When said switch bridges contacts 37 and 38, current flows from battery 80 through conductors 90 and 82 to the motor 42, spreading through conductor 83, contacts 55, a conductor 84, a conductor 85, electro-magnets 64, a conductor 86, contact 36, a conductor 87, contact 37, switch 22, contact 38 and conductor 81 back to the motor 42 and at the same time spreads from switch 22 through a conductor 88, contacts 34 and 33, and a conductor 89, back to the battery 80. As motor 42 operates, its shaft 42 through the medium of the worm 50 drives gear wheel 49 which imparts movement to the shaft 46, gear wheel 51 thereon and gear wheel 52. The gear wheel 52 during rotation at cam 54 alternately engages and disengages the contact 55 to move the latter with respect to contact 56 so as to alternately make and break the said electric circuit to thus periodically energize the magnet 64. By energization of the magnet 64, the armature 63 is alternately attracted by it, and retracted by means of the spring 68 acting on arm 65. Each attraction stroke of the armature causes the pawl 66 to advance the ratchet wheel 62 one tooth and accordingly advance or rotate the shaft 59. Retrograde movement of said shaft 59 is prevented by the pawl 73 in cooperation with ratchet wheel 72. After each attraction of the armature 63, and the breaking of the circuit to the electro-magnet 64, such armature 63 is restored to normal position pre-

paratory to the next actuation by the spring 68.

Referring now to the registering mechanism, a bracket mounting therefor consists of an attaching plate 91 secured to the base 1 and side plates 92 and 93 extending forwardly therefrom. A shaft 94 is journaled in said side plates 92 and 93 for rotation in one direction but held against retrograde movement by means of a ratchet wheel 95 (Figure 6) and cooperating spring pawl 96 (see Figure 6) respectively, mounted on said shaft 94 and side plate 92. Journaled on said shaft 94 to turn in one direction is a suitable plurality, preferably three of the number or recording drums 14 aforesaid, which it will be realized, are operated by electro-magnet 64, or as will later appear, from the wheel of a taxicab when the motor 42 is idle. Said drums 14 on their periphery preferably have numbers delineated from zero to nine as shown. Each drum 14 has a hub 98 projecting beyond the open side thereof and a ratchet wheel 99 on and rigid with said hub (Figure 13). Plates 92 and 93 mount a rod 100 on which a plurality of pawls 101 are pivoted which engage said ratchet wheels 99 and are urged into engagement therewith by means of springs 102 surrounding rod 100, each spring having one end secured intermediate the base 1 and plate 91 and the other end disposed over pawl 101. Shaft 94 (Figure 24) has a longitudinally extending groove 103 (Figure 24), one wall of which is straight and substantially radially disposed and the other wall of which curves from the base of said wall to the periphery. Spring pressed pawls 104 are carried by the drums 14 and pass through suitable slots in hubs 98 and enter the groove 103.

An actuating frame (see Figures 7 and 11) is provided comprising arms 105 and 106, journaled on said shaft 94. These arms are joined by a rod 107 and thereon a plurality of fingers 108 are journaled from which the spring pawl 109 extends and engages said ratchet wheels 99. This frame is urged forward by means of a contractile spring 110 secured to arm 106 and to a bracket or extension 111 projecting forwardly from the bearing or plate 61. Forward movement of the arm 106 and frame of which it forms a part is limited as by means of a stop in the form of a set screw 112 mounted in a depending arm 113 of the bracket 67.

Rigidly secured on the shaft 59 is a cam 114 preferably provided with two points or lobes as best shown in Figure 13, which points are adapted to alternately engage the arm 106 during rotation of the shaft 59 in order to depress or move the arm 106 rearwardly. During rearward movement of the actuating frame, the pawls 109 idle over the ratchet wheels 99 but when they are released, they engage the teeth of said ratchet wheels and

advance the same on the return movement of the actuating frame under urging of the spring 110. It will be understood that the arrangement of the wheels 14 is such that viewing them in Figure 13, the innermost wheel first makes a complete revolution and then imparts movement to the central wheel and upon completion of its revolution, the third wheel is actuated, the structure being but generally shown, details being omitted for the sake of clearance and as forming no part of the invention itself. After the pawls 109 advance the ratchet wheels 99 and wheels 14 rigid therewith, retrograde movement of said wheels is prevented by the pawls 101 as will be understood. Journaled on the shaft 94 is a gear wheel 115 which is rigid with a relatively large disk 116 (Figures 5, 13 and 16). On said disk a spring pressed pawl 117 is provided which cooperates with grooves 103. A stub shaft 118 on the side plate 93 journals a gear wheel 119 in mesh with said gear wheel 115 and also in mesh with the teeth of a rack bar 120. Rack bar 120 slides against the inner longitudinal edge of a suitably shaped track member 121 overlapped by a guard flange or bar 122. The rack bar 120 is provided with a cap member 123 (Figures 9 and 10) and a contractile spring 124 is secured at 125 to said cap member and at 126 to the track 121.

Said spring 124 normally maintains the rack bar 120 in engagement with the lug 127 of a lever 128 provided with a wedge end 129. Said lever 128 is pivoted at 130 on an arm 131 extending from the base 1 (Figure 5). The wedge end 129, as shown in Figure 7, is interposed between the side plate 93 and a slidable detent plate 94^a. Wedge lever 128 is urged upwardly by means of a coil spring 132 secured to said lever 128 and side plate 93. To limit downward movement of lever 128, at one end, a set screw 133 is provided which is adjustable, as shown in Figure 5, in the path of lug 127.

Detent plate 94^a is slidably mounted by means of set screws or the like 134 passing therethrough and into a bar 135 mounted by and intermediate side plates 92 and 93 (Figure 7). The plate 94^a has elongated slots 136 through which said set screws 134 pass. A contractile spring 137 secured to the plate 94^a and guide plate 93 normally maintains the detent plate in contact with the wedge 129.

It is to be noted that a plurality of projections 138 one for each number on drums 14 is provided on said drums and the detent plate is normally disposed in the path of movement of said projections so as to prevent movement of drums 14.

A guard member having a terminal loop 138^a is provided on the upper end of the rail or track member 121.

The rack bar 120 in any suitable manner 130

operates the register 26 but primarily it is adapted to be actuated to reset the number drums 14. To this end, an arm 140 (Figures 9 and 10) is extended from disk 28 and has a lifting lever 141 pivoted thereon at 142. A pin 143 is provided on arm 140 to which a spring 144 is secured which is also secured at 145 to the lever 141 in order to urge the lever 141 into engagement with the said pin 143 and receive it in a notch 146. As will be noted from Figure 9, when the flag 17 is raised, the lever 141 is at an angle to arm 140 and resting on the arm 67.

The arm 106 as seen in Figure 7, is extended and provided with a cam 147, (also see Figure 11) to cooperate with a slot 148 in the detent plate 94^a. Projections 138 cooperate with slots 149 in said detent plate in that the drums 14 may turn only when said slots 149 align with the respective projections 138.

The resetting operation is as follows. When the flag 17 is moved from the full line position shown, that is from the inoperative position to the operative or dotted line position, the disk 28, arm 140 and lever 141 move. Said lever 141 in its upward movement engages the cap 123, (Figures 9 and 10) thus sliding the rack bar 120 upwardly against the tension of the spring 124. In moving upwardly, said rack bar 120 disengages the lug 127, whereupon the spring 132 moves the lever 128 upwardly causing the wedge 129 to move the detent plate 94^a to the right as in Figure 7 against the tension of spring 137, whereby the openings 149 will be disposed in the path of movement of the lugs 138 and thus will offer no obstruction to their rotation or movement. Continued upward movement of the rack bar 120 through the medium of gear wheels 119 and 115, rotates disk 116 independently of the shaft 94, with the pawl 117 idling over the shaft 94. Slight further movement upwardly of lever 141 from the position shown in Figure 10 will disengage same from the cap 123 whereupon the spring 124 will urge the rack bar 120 downwardly thus rotating the gears 119 and 115 and disk 116 in the opposite direction causing the pawl 117 to coact with groove 103 of shaft 94 to move the drums 97 to an initial or reset position. As the rack bar 120 descends it engages the lug 127, thus depressing lever 128 against the tension of the spring 132, lowering the wedge 129, whereupon the spring 137 urges the detent plate 94^a to the left disposing unslotted portions thereof in the path of movement of projections 138 to prevent further movement of the drums 97 until the succeeding operation.

The actuating frame for the number or registering drums moves rearwardly with the cam 114 and the foot 147 coacts with the adjacent walls at the recess 148 to move the detent plate 94^a to the right in Figure 7 so that the slots 149 will be in the path of move-

ment of projections 138 so that the drums 97 may advance.

Journalized in plate 93 is a shaft 153. This shaft is also journalized in the track rail 121 adjacent the lower end thereof. A spring 70 pressed pawl 120^a (Figure 5) is provided on rack bar 120 so as to idle past a ratchet 149^a on shaft 153 in one direction and so that as said rack bar descends it will advance the ratchet wheel 149 to advance one of the registering wheels or drums 25 one number. A spring pressed pawl 150 on rail 121 prevents retrograde rotation of shaft 153 and pawl 149^a. Shaft 153 is further supported by bearings 151 in which both of the shafts 94 80 and 153 are journalized. On said shaft 153, the drums of the registering mechanism 24, visible through the opening 22^a, are journalized. The rotation of certain parts of the registering mechanism is controlled by idler 85 gear wheels 152 journalized on shaft 153 and adapted to mesh with teeth 154 provided in the sides of said registering wheels. One portion of said registering mechanism is adapted to be driven through movement of the actuating device of the registering drums 14. To this end, the shaft 94 has a ratchet wheel 155 journalized thereon with which a gear wheel 156 is rigid. The pawl 109 of the adjacent finger 108 is relatively wide and in addition 90 to engaging said ratchet wheel 155 it also engages the adjacent ratchet wheel 99 so that both of these ratchet wheels will be simultaneously operated and will turn the gear wheel 156. The gear wheel 156 in turn 95 drives a gear wheel 157 (Figure 11) journalized as at 158 to the adjacent plate. Such gear wheel 157 together with a gear wheel 159 pivoted at 160 to the adjacent bearing plate 151, and a shaft 161 (Figures 7 and 11) 100 has driving engagement in any desired way 105 with the aforesaid registering mechanism 24, specifically forming no part of the invention.

Said shaft 161 is mounted in side members 110 or walls 162 and 163 of a suitable mounting bracket supported from the base 1 as by a lower wall 164. Gear wheels 165 and 166 are keyed on the shaft 161. A gear wheel 167 journalized at 168 on side members 162 meshes 115 with gear wheel 165 to operate a part of said registering mechanism 24. On the other hand, a gear wheel 169 journalized at 170 on side wall 163 meshes with gear wheel 166 to operate another part of said registering 120 mechanism 24.

On shaft 161, a clutch head 171 is slidable 125 having a sleeve provided with an elongated slot into which a pin on shaft 161 projects. Said pin extends from a sleeve 174, in telescopic relation with clutch head 171. The sleeve 174 is carried by a gear wheel 175, keyed on shaft 161. On shaft 161, a clutch head 176 is provided having teeth 177 to cooperate with the teeth of the head 171 in 130

order that rotation of gear wheel 175 may be imparted to the clutch head 176. The driving of gear 175 in the manner aforesaid drives shaft 161, gears 165 and 167 and the latter operates the parts of the registering mechanism 24. When the flag 17 is raised, the clutch heads 171 and 176 are disengaged. Lowering of said flag engages clutch heads 171 and 176 since this movement causes slide 198 to be depressed, thereby causing engaging movement of slide 189 and clutch head 171. With the clutch heads thus engaged, shaft 161 drives the gears 167 and 169 which results in driving other parts of the registering mechanism 24. In mesh with gear wheel 175, which is a worm wheel, is a worm 177^a mounted on a shaft 178 journaled in the wall 164 and a bearing 180 carried by bar 135. Below wall 164 a gear wheel 181 is keyed or fixed to shaft 178 and retrograde movement thereof is prevented by means of a spring pawl 182 secured to the base 1. Journaled on the shaft 178 below the wall 164 is a lever 183, movement of which is limited in one direction by a pin 184 depending from wall 164 (Figure 15). A spring pawl 185 is mounted on lever 183 and is normally disposed in engagement with the gear or ratchet wheel 181 as best shown in Figure 15. An electro-magnet 186 is mounted as by an arm or bracket 187, from the wall 164 and its armature 188 is mounted on the lever 183, whereby upon energization of the magnet 186, armature 188 will be attracted which will cause the pawl 185 to advance the wheel 181 and impart movement to the shaft 178 and mechanism in gear therewith.

In order to shift the clutch head 171 into and out of engagement with the clutch teeth 177, an actuating slide 189 is provided and movable on the under surface of the wall 164 being fastened by a set screw 190 disposed in an elongated slot 191 in the slide 189. Passing from the slide through an opening 192 in the wall 164 is a fork or bifurcated arm 193 which engages in a groove 194 of the head 171.

The actuating lever or slide 189, as best shown in Figures 7 and 15 receives an arm of a lever 195 in the slot of a fork 196 on the slide 189. This lever is pivoted at 196^a to the side member 162. A spring 197 may be secured to the lever 195 and bar 135 for normally maintaining clutch head 171 out of engagement with the clutch teeth 177.

A bar or slide 198 operable to depress the lever 195 is provided with elongated slots 197^a through which set screws 198^a (Figure 6) pass to mount the same, one of said set screws entering the supporting plate 39, and the other entering a stud 199 on side plate 92. Adjacent the upper end of the bar 198 is a slot 200 into which a lug 201 of a depressible actuating plate 202 extends. This plate is normally disposed in the position shown in

Figure 17 and is secured to the back of the supporting plate 39 by means of set screws or the like 203 passing through elongated slots 204 in the plate. The action of spring 197 normally maintains the plate 202 in elevated position. Said plate 202 is operable for depression into the dotted line position shown in Figure 17 so as to depress the bar 198, lever 195, shift the slide 189, and slide the clutch head 171. The plate 202 is depressible as the flag 17 is thrown to the right when it is desired that the apparatus should operate, through the medium of a stud or projection 205 on disk 28. When the flag 17 is raised, the clutch heads 171 and 176 are disengaged. Lowering of said flag engages clutch heads 171 and 176 since such movement causes slide 198 to be depressed, thereby causing engagement of slide 189 and clutch head 171. With the clutch thus thrown in, shaft 161 drives the gears 167 and 169, which results in driving certain totalizers or parts of the registering mechanism 24.

With the switch 20 to the right in Figure 4, blade 22 bridges contacts 33 and 36. Such movement of the switch 20 opens the circuit to the electric motor so that it will not operate while the taxicab is running. At the same time, an electric circuit through the battery is established including magnet 64 and magnet 186. The current passes from the switch, through contact 33, conductor 89, battery 80, conductor 90, conductor 206, magnet 186, conductor 207, conductor 208, conductor 85, magnet 64, and conductor 86 to the contact 36. Thus both gear wheels under such circumstances, namely at 62 and at 181, will be driven by the cooperation therewith of the electro-magnets and their armatures. In the circuit last mentioned however a make and break device is provided so that the electro-magnets 64 and 186 will alternately attract and repel their armatures. Such a device is diagrammatically shown in Figure 4 and specifically shown in Figures 19, 20 and 21. Such device includes spaced contacts 209, normally disengaged and being engageable by the working of a finger 210 against one of them.

The make and break device involving said contacts 209 and finger 210 is preferably attached to and driven from a wheel of the taxicab or vehicle to which the apparatus is applicable but only when the circuit of motor 42 is open or in other words only during "running time". A sleeve 211 may be provided, extending from a base plate 212, and having a removable cover plate 213. The plates 212 and 213 are secured together by means of set screws 214 passing through a spacing block 215 and into an arm 216 which is in any suitable manner attached to the wheel of the taxicab or other vehicle as referred to. The shaft carrying said finger 210, is provided at 217. Rigid with shaft 130

217 is an actuating wheel 218 disposed intermediate the bracket 216 and base plate 212. The wheel 218 has a plurality of spaced leaves or spokes 219.

5 To cooperate with the wheel 218, a cam ring as shown in Figures 22 and 23 is provided, being attachable to the vehicle wheel concentric with the hub by means of bolts or the equivalent passing through tangs 221 thereon. The cam track 220 at its terminals is connected by a plate 222 which spaces them apart. Wheel 218 is disposed substantially radially with respect to cam 220 with the latter disposed between two of the 10 spokes 219 as in Figure 19, whereby the cam in actuation serves as a spiral passing successively through the spaces between spokes 219 so that wheel 218 will thus be slowly rotated so as to impart its motion to the 15 shaft 217 to close the contacts 209, to establish the electric circuit through the two magnets in a make and break manner.

A shutter 222^a is adapted for disposition over the openings 12 and 13 when the flag 17 is raised and it may contain the word "Vacant" 20 thereon to be viewed through said openings, as suggested in Figure 7. When the flag 17 is down, such shutter 222^a occupies the dotted line position shown in Figure 11. It may 25 also be mentioned that the sign 16 is carried by the shutter 222 and is adapted to be displayed at the opening 12, as shown Figure 1, when said shutter is in the dotted line position of Figure 11, that is lowered. Said 30 shutter has an arm 223, which is adapted to engage the adjacent finger 108 when the shutter is disposed in the rear of opening 12 so as to move the adjacent pawl 109 out of engagement with the coacting ratchet wheel 99, so as to enable resetting action of the 35 wheels 97 to be effected.

The shutter 222^a has side flanges 224 pivoting it at 225 to the side plates 92 and 93. One flange 224 has a lug 226 (Figure 6) 40 which enters a slot 226^a in an arm 228 secured to bar 198. Thus as the flag 17 is moved to the right and bar 198 is depressed, the shutter will also be moved to its lowered position which will expose the sign 16 at opening 12.

As at times an extra fare or tariff is charged which is not fully indicated by the registering wheels or drums 14, a mechanism is provided whereby said registering wheels 45 or drums 14 may be moved faster than normal as previously described in order to correctly show the fare. To this end, the stop screw 69 is carried by the aforesaid slide or bracket 71 which is secured in place as best seen in Figure 14, by studs 231 passing through an elongated slot 232 therein, and which fasten a plate 233 over the bracket 71 to retain the same in place. The bracket 71 is normally urged toward the armature 63 by a spring 234 secured to the bracket 71 and

to one of the studs 231. A screw or connecting member 235 extends from the bracket 71 to a swivel head 236 on a lever 237 (Figure 9) pivoted at 238 to the base 1. Movable against the upper free end of the lever 237 is a cam 238^a and the lever is normally maintained in engagement with the cam by means of a spring 239 fastened to the lever and to a stub shaft 240 carrying the cam and which is journaled on the base 1 and exteriorly thereof has an operating handle 24 as clearly shown in Figure 2. In Figure 9, the parts are so disposed that the bracket 71 and stop 69 are set to limit movement of the armature 63 to the normal extent. In the event that it is desired to increase the price and permit the registering wheels or drums 14 to move more rapidly, the handle 24 is thrown upwardly into the position shown in Figure 10, thus moving the cam 238^a as shown in said figure to a position tilting the lever 237 and drawing the bracket 71 away from the armature 63 which will provide greater space for its operation and consequently enable the ratchet wheel 62 to be turned to a greater extent each time the armature 63 is actuated.

A means is provided whereby extra charges may be registered and which means is preferably operable manually. It utilizes the drum 15 on the periphery of which suitable amounts may be delineated. Rigid with the drum 15 is a ratchet wheel 229^a which is normally held against retrograde movement by means of a pawl 230^a journaled on rod 100 and normally held in engagement with the ratchet by means of a coil spring 231^a similar to the coil spring 102. For said drum 15 an actuating frame, is provided consisting of arms 232^a and 233^a loosely journaled on the shaft 94 and on which said drum 15 is loosely journaled. This actuating frame is normally spaced from cam 114 as shown in Figure 13 to avoid improper operation of drum 15 simultaneously with wheels 14. The drum 15 has a spring pressed pawl 234^a adapted to pass through a slot of the hub to engage the groove 103 of shaft 94. Said arms 232^a and 233^a are connected by rods or shafts 235^a and on the rods pawls 236^a and 237^a are journaled. The pawl 236^a 110 engages the ratchet wheel 229^a, to actuate the wheel each time the frame is actuated. Said pawl 237^a engages a ratchet wheel 238^b loosely mounted on the shaft 94 and having a gear wheel 239^a rigid therewith which meshes with the said gear wheel 159 previously described in order to actuate the number drums 24. The drum 15 is normally held against retrograde movement by the detent plate 94^a when the actuating frame for the drum 15 is moved.

The cam foot 240^a of the arm 233^a engages a wall of slot 241 in said cam plate and slides the same so that a slot 242 in the detent plate 120

will be opposite the projections 243 on the drum 15 corresponding to projections 138, so that the drum 15 may be advanced. In order that the actuating frame for the drum 15 may normally remain in and keep a forward position as in Figure 13, a coil spring 244 is connected to the extension 111 and to the arm 233^a (Figures 7 and 8). A stop 245 to limit forward movement of the actuating frame for drum 15 is provided on the side plate 92.

In order to actuate the frame for said drum 15, a slide 246 (Figure 18) is provided having an actuating plunger stub 247 which is slidable in an opening in the base 1 and projects to the rear thereof. The slide 246 also has an elongated slot 248 into which a pin 249 mounted on side plate 92 extends. The slide or plunger 246 is capable of lateral play on the pin 249 in order that the hook or cam end 250 may be projected to the dotted line position of Figure 18 in order to move in front of and across the arm 232^a. The slide 246 is movable against the tension of a spring 251 secured to the slide and to the base 1, preferably having its axis diagonal so that as the slide plunger 246 is pushed forward, the spring will urge it toward and in front of the arm 232^a.

It will be realized that upon pressing the stub inwardly by means of the thumb or otherwise, the plunger 246 will move to the dotted line position of Figure 18 and when released the spring will pull the arm 232^a rearwardly a short distance, and then release it, whereupon the spring 244 will return the actuating frame for the registering drum 15 to normal position. In this way, successive operations of the plunger stub 247 will bring the desired extra amounts to be charged into view at the opening 13.

Briefly to resume the general operation and functions performed and necessarily omitting much specific description as heretofore given, the electric wiring is so arranged that when said flag 17 is down as in dotted lines in Figure 1 and full lines in Figure 2, and switch 20 is thrown to the right in Figure 1 and engages contact 36, the double electro-magnet 64 and the single electro-magnet 186 are connected in series with the battery 80. When such switch 20 is thrown to the left, it engages contacts 37 and 38 thus energizing electric motor 42 so that through the gearing shown, said gear 52 is also driven. Said gear 52 presses the cam 54 against the contact points 55 so that it engages contact 56 which causes the electro-magnets to attract their armatures and drive their respective sub-mechanisms or parts. The circuit at device 209—210 is operated from the wheel of the motor vehicle equipped with our improved apparatus and such device will be opened and closed a certain number of times per minute. Such closing of the circuit en-

ergizes magnet 64 but does not energize magnet 186. Said magnet 186 is provided to be cut into the circuit at proper times so that it will always operate with the front wheel of the vehicle at device 209—210. Thus when the flag 17 is up none of the electrical apparatus operates except magnet 186 which it is to be noted is so connected that it operates irrespective of the position of the flag 17. When the switch closes the circuit of motor 42, the latter drives gear 52 so as to close the circuit at contacts 55 and 56 which causes magnet 64 through the gearing shown to drive shaft 59 which through cam 114, depresses actuating frame 105—106 to operate so registering drums 14 thereby moving the third roll 14 from the left in Figure 7 forward one number each time, after which the actuating frame is spring-returned to normal position. Said drums 14 are so arranged that after said third drum from the left advances one number, the second roll from the left advances one number and so on with the remaining roll until they complete the figures "999".

The zero plate 16 as it is carried by the shutter 222^a serves to lift and maintain lifted the control arm 108 (Figure 11) of actuating frame 105—106 when the said shutter and flag 17 are raised so that when the resetting mechanism operates the frame 105—106 to its starting position, arm 108 which throws the third drum 14 from the left, will not throw said drum or the small gear connected to the registering rolls. When said flag 17 is raised, the slide 198 is moved upward carrying shutter 222^a upward to "Vacant" position and pulls the clutch out thus disconnecting the registering mechanism. When flag 17 is thrown to the right, which turns disk 28, lifting lever 141, into engagement with cap 123 and thereupon lifting rack bar 120 to a point, as in Figure 10 where the lever 141 disengages said cap and rack, whereupon the rack bar 120 due to gravity and the urgency of spring 124 descends and through coaction with the gear wheels shown picks up the various fare drums or registering wheels and drives them to normal position, thus resetting such drums or wheels. The rack bar 120 also actuates lever 128 because of its wedge 129 so as to move the detent bar or plate 94^a to drum-unlocking position until bar 120 has descended and the drums are re-set. Then rack bar 120 pushes wedge 129 to one side and allows detent plate 94^a to slide in before the projections 243 stop them. Also when the flag 17 is thrown to the right arm 35 depresses contact 34 against contact 33 which makes connections with battery 80 between the double electro-magnet 64 and the contact magnet device 209—210 on the front wheel of the vehicle so that each time the cam at the said front wheel makes a contact, the armature 63 which through in-

termediate mechanism moves the driving shaft 59 on which is fastened cam 114 which depresses the actuating frame 105—106 a certain distance each time. When a certain number of these contacts have been made, 5 said cam 114 depresses the frame 105—106 to a point where they drop off and allow the frame to rise and carry the fare or registering drums forward.

10 The electric motor 42 and its contact arrangement is such that when the switch 20 is thrown to the "waiting time" side, the electric motor revolves and drives the gear 52 which closes the circuit of the double electro-magnet 64 and a certain number of 15 times per minute causes the electro-magnet 64 to attract the armature and drive the shaft 59.

20 As to registering extra amounts, plunger 246 when pressed inwardly by the thumb moves to the dotted line position of Figure 18 and when released the spring 251 will pull the arm 232^a rearwardly a short distance and then release it whereupon the spring 244 will 25 return the actuating frame for the registering drum 15 to normal position. Successive operations will thus bring the desired extra amounts to be charged into view at the opening 13.

30 As merely one practical embodiment has been illustrated and described, in view of the fact that many changes in the details, combinations and arrangements of the parts may be resorted to, it is to be understood that the 35 same are reserved provided they fall within the spirit and scope of the invention.

What is claimed is:

1. A registering device having registering mechanism electro-magnetic means to actuate the same including normally spaced contacts, a base, a stub shaft journaled in said base, means carried by the stub shaft abutting the base exteriorly, a disk slidable on the stub shaft and abutting the inner surface of the base, an expansive spring on the stub shaft to maintain the disk in frictional engagement with the base, and means to control the operation of the contacts carried by said disk.

2. A registering apparatus having a registering mechanism, electro-magnetic means to actuate said mechanism including normally spaced contacts, a base, a stub shaft journaled in said base, said stub shaft having a head exteriorly of the base and abutting the same, a disk slidably keyed on said stub shaft and abutting the opposite surface of said base, the stub shaft extending in advance of the base and having a flange, an expansive spring surrounding said stub shaft and abutting said flange and said disk to maintain the latter in frictional engagement with the base, and means carried by the disk to control actuation of said contacts.

3. A registering apparatus having a regis- 65 tering mechanism, a base to mount the

same, a supporting plate, posts spacing said supporting plate from said base, an electric motor on said supporting plate, a stub shaft journaled in said base having a head abutting one side thereof, a disk slidably mounted on said shaft abutting the other side of said base, said stub shaft being extended from the base toward the supporting plate and having a flange, an expansive spring surrounding said shaft and abutting said flange and said disk to maintain the latter in frictional contact with said base, a switch for said motor on said base, means on said disk to control closing of said switch, and a make and break device to control actuation of the registering mechanism having parts driven by said motor and normally spaced contacts cooperating therewith and carried by said supporting plate.

4. A registering apparatus for use on a vehicle including fare registering mechanism, an electro-magnetic means to actuate the same, a bracket movable relatively to said means to limit the throw of the armature, a control lever for the bracket, and means operable against the said lever to shift the same.

5. A registering apparatus for use on a vehicle including fare registering mechanism, an electro-magnetic means to actuate the same, a slide bracket, a base, means passing through said slide bracket from said base to mount the same, said bracket having an elongated slot through which said means passes, a lever operatively connected to the slide bracket, a cam operable against the lever, a spring to maintain the cam and lever in contact, and an operating means for said cam.

6. Registering mechanism having a registering wheel to indicate extra charge, an actuating frame for said wheel, a slide having a hook movable into engagement with said frame, said slide having an elongated slot, guide means extending into said slot, and a retractile spring for said slide.

7. Registering mechanism having a registering wheel to indicate an extra charge, an actuating frame for said wheel, an operating member for said frame normally disengaged therewith, means to urge retraction of the element when engaged with the frame, and means causing said frame to be moved through the retraction of said element.

8. A registering apparatus having a registering mechanism, a flag device, a slide, means to depress the slide through actuation of the flag device, a shutter controlling said registering mechanism, means operable by the slide to displace the shutter to operatively set the registering mechanism, auxiliary registering mechanism, and a clutch for the latter mechanism under control of said slide.

9. A registering apparatus having a regis-

tering mechanism, a flag, a slide under control of said flag, a shutter for said mechanism in its "vacant" position maintaining said mechanism inoperative, said shutter being under control of said slide, said mechanism being adapted to be set as the shutter is lowered through movement of the slide, an auxiliary registering mechanism, means to drive said latter mechanism including a clutch, and means operable by the slide to control said clutch.

In testimony whereof we affix our signatures.

CLARENCE E. JOHNSON.
